UNITED STATES PATENT OFFICE.

THOMAS J. GREENE, OF BELLEVUE, PENNSYLVANIA.

PNEUMATIC PLAYER ACTION.

Application filed May 28, 1923. Serial No. 641,954.

This invention relates to player pianos, and has for its object to provide an improved pneumatic unit, and improved means for supporting such units in proper relation to the vacuum chest.

The pneumatic unit is composed of separable sections or layers which may be quickly taken apart to permit access to the valve and pouch, and as quickly united again after cleaning or repairing has been done. Heretofore sectional pneumatics have been glued or otherwise permanently fastened together precluding cleaning and repairs being readily made thereto. When said former construction is used and any one of the pneumatics fails to operate properly it must be replaced by a new one, whereas my improved pneumatic may be used for a much longer time because it can be taken apart for cleaning and repairs and afterwards reassembled when it is as serviceable as before. Furthermore, my pneumatic unit is made entirely of wood, so that it costs much less to manufacture than prior constructions having metal parts which corrode and cause the valves to stick.

The pneumatic units are detachably secured to the vacuum chest by fastening means each of which serves to support adjacent units, so that by taking out two of said fastening means any one of the pneumatics may be removed from the piano for inspection. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a longitudinal vertical section of a pneumatic unit constructed substantially in accordance with this invention and assembled or attached to the vacuum chest which is shown in transverse section.

Figure 2 is a top plan view of one of the pneumatic units.

Figure 3 is an elevation of a plurality of pneumatic units as they appear looking at the right hand end of Figure 1 and showing the detachable fastening means or

screws for attaching them to the vacuum chest, and

Figure 4 is a top plan view of a plurality of the pneumatic units supported in operative position at one end by said detachable fastening means connected to the vacuum chest and at the other end by projecting pins engaging a rail extending parallel to said chest as shown in Figure 1.

The body of the pneumatic unit 1 is composed of a plurality, preferably two layers or sections of hard wood 2 and 3 which are detachably secured together by screws 4, preferably four in number. The upper section 2 has two angular passages 5 and 6 formed longitudinally thereof and overlapping one another at their adjacent ends. The passage 5 has a horizontal portion 7 opening on the upper face of the section 2, and a vertical portion 8 extending entirely through said section and opening on the lower as well as the upper face thereof. The passage 6 has a horizontal portion 9 underlying but spaced from the horizontal portion 7 of the passage 5, and another horizontal portion 10 arranged at a higher level than the portion 9 and connected thereto by an inclined portion 11. The horizontal portion 10 of the passage 6 extends near to the right hand end of the section 2 as it appears in Figure 1 and beyond the corresponding end of the lower section 3 of the pneumatic unit. The portion 9 of the passage 6 communicates with the portion 7 of the passage 5 overlying the same by means of an opening 12 having a valve seat 13 formed at its upper end.

The section 3 of the pneumatic unit body has a vertical passage 14 extending entirely through it and registering with the vertical portion 8 of the passage 5 in the upper section 2. Said section also has an angular passage 15 formed therein, the same comprising a comparatively long vertical portion 16, opening on the upper face of said section below the horizontal portion 9 of the passage 6 in the section 2, and a horizontal portion 17 extending from said vertical portion 16 to the right hand end of the section 3 as shown in Figure 1. Said horizontal portion 17 of the passage 15 communicates with the inclined portion 11 of the passage 6 in the section 2 by means of an opening 18 preferably reduced in size by a filler element 19 having a pin-hole 20.

The portion 16 of the passage 15 in the

lower section 3 is covered by a flexible dia-
phragm or pouch 21 which cuts off the pas-
sage of air therefrom to the overlying por-
tion of the passage 6 in the upper section 2.
5 On said diaphragm or pouch the wooden
stem 22 of the valve 23 rests, said valve be-
ing also made of hard wood and adapted
to seat on the valve seat 13 in the portion
7 of the passage 5 in the section 2, and said
10 stem extending through the opening 12 be-
tween the passages 5 and 6. A gasket 24
is arranged between the sections 2 and 3
to make an air tight joint between them
when they are fastened together by the
15 screws 4, it being understood that said gasket
has openings therein corresponding to the
communicating passages in the two sections.

A bellows 25 is attached to the lower face
of the lower body section 3 of the pneumatic
20 unit in the usual manner, said bellows com-
prising a bottom plate 26 and a flexible mem-
ber 27 by which said plate is hinged to the
lower section 2 of the unit. A projecting
lug 28 on the free end of the plate 26 is
25 designed to have operative connection with
the hammer action of one key of a piano in
any well known manner.

The horizontal portion 7 and the upper
30 end of the vertical portion 8 of the passage
5 in the upper section 2 of the pneumatic
body are covered by a plate 29 detachably
fastened in place by screws 30. Said plate
29 has an opening 31 therein communicating
35 with the passage 5 in vertical alinement with
the valve 23 and of less diameter than said
valve, so that the latter will cover and close
said opening when raised.

The section 2 of the pneumatic body also
40 has a vertical passage 32 leading from the
right hand end of the passage 6 to the up-
per face of said section, and in said passage
there is fitted a tubular member 33 adapted
45 to also fit in an opening 34 in the bottom of
the vacuum chest 35. A horizontally pro-
jecting pin 36 at the left hand end of the
section 2 is adapted to engage a socket in
50 the inner face of a rail 37 suitably sup-
ported in the piano (not shown) and extend-
ing parallel to the vacuum chest at a slight-
ly lower level.

The left hand ends of the pneumatic units
are supported by their pins 36 engaging the
rail 37, while the right hand ends of said
units are supported below the vacuum chest
55 35 by detachable fastenings or inverted
screws 38 best shown in Figure 3. Each of
said screws is arranged between two adj-
acent units, and its head 39 or a washer 40
supported thereby is adapted to engage both
60 of said units below the overhanging right
hand end portions of the sections 2 thereof,
see Figures 1 and 3. With this arrangement
the units may be placed very close to-
gether, reducing the space occupied by them
65 in the piano, and the number of the sup-

porting or fastening screws 38 is also re-
duced. It will also be seen that any one of
the units may be readily removed by first
70 taking out the two screws 38 at opposite
sides thereof, then swinging the right hand
end of said unit downward slightly to dis-
engage the tubular member 33 from the
vacuum chest and finally removing the pin
36 in the left hand end of said unit from
75 the rail 37. The pin 36 has sufficient flex-
ibility to permit the slight downward swing-
ing of the unit mentioned.

A tubular member 41 is fitted in the end
of the horizontal portion 17 of the passage
15 and is designed to have the usual tube
leading to the tracker bar (not shown) at-
tached thereto. The normal inactive pos-
itions of the parts of the pneumatic unit are
80 shown in Figure 1, the inlet of air to the
vacuum chest being cut off by the seated
valve 23 and the corresponding opening in
the tracker bar being closed by the music
strip (not shown). When the opening in
85 the tracker bar leading to the tubular mem-
ber 41 is uncovered during the progressive
movement of the music strip in the well
known manner, air is admitted below the
diaphragm, causing the suction in the vac-
uum chest to raise said diaphragm and to un-
90 seat the valve 23, whereupon the suction from
said vacuum chest acts through the passages
6, 5 and 14 and opening 12 to collapse the
bellows 25 and actuate the hammer engaged
by the lug 28. During this operation of the
95 hammer, the opening 31 in the plate 29 is
closed by the valve 23. When the opening
in the tracker bar is again covered by the
music strip, the air below the diaphragm is
exhausted by suction from the vacuum
100 chest acting through the pin-hole 20 and the
valve 23 drops again to its seat where it is
held by said suction, while air is admitted to
the bellows through the opening 31 and pas-
sages 5 and 14, permitting said bellows to
105 expand and the plate 26 to drop into posi-
tion for again actuating the hammer when
next raised.

It will be observed that access may be had
to the valve of any unit by simply taking out
the screws 30 and removing the cover plate
110 29 without removing the unit from the piano,
and that when said unit has been removed
from the vacuum chest and supporting rail,
as already explained, access may be had to
the diaphragm or pouch by simply removing
115 the screws 4 and taking apart the sections 2
and 3.

I claim:

1. A pneumatic unit for player pianos
120 comprising superposed detachably connect-
ed sections, the upper section having two
superimposed recesses therein and a passage
extending between them, a valve arranged in
the upper of said recesses and having its
125 stem projecting through said passage into the
130

other recess of the same section, the lower section of the unit having a recess disposed below the recess in the upper section into which the valve stem extends, a valve-supporting diaphragm covering said recess in the lower section, a vacuum chest communicating with the recess in the upper section of the unit into which the valve stem projects, a bellows communicating with the other recess in said upper section, means of communication from the recess in the lower section to the tracker bar of a piano, and reduced means of communication between said recess in the lower section and the recess in the upper section which communicates directly with the vacuum chest.

2. A pneumatic unit for player pianos comprising superposed detachably connected sections, the upper section having separate recesses therein in overlapping relation and a passage extending between them, a valve arranged in one of said recesses of the upper section and having its stem pro-

jecting through said passage into the other recess of the same section, the lower section of the unit having a recess disposed below the recess in the upper section into which the valve stem extends, a valve-supporting diaphragm covering said recess in the lower section, a vacuum chest communicating with the recess in the upper section of the unit into which the valve stem projects, a bellows communicating with the other recess in said upper section, means of communication from the recess in the lower section to the tracker bar of a piano, and reduced means of communication between said recess in the lower section and the recess in the upper section which communicates directly with the vacuum chest, the valve and contacting parts of the unit being made of wood for the purpose specified.

In testimony whereof I have signed my name to this specification.

THOMAS J. GREENE.
